ELECTRON DISCHARGE TUBE

Paul W. Stutsman, Needham, Mass., assignor, by
mesne assignments, to Raytheon Manufacturing
Company, Newton, Mass., a corporation of
Delaware

Application May 5, 1944, Serial No. 534,292

6 Claims. (Cl. 250—27.5)

1

This invention relates to electron discharge tubes.

One object of the invention is to provide an electron discharge tube with an auxiliary electrode that will produce a greater flow of electrons from the cathode to the plate and a relatively high ratio of increase in plate current to current drawn by said auxiliary electrode, so that current drawn by said auxiliary electrode is unobjectionable.

This and such other objects of the present invention as may hereinafter appear will be readily understood from the following description taken in connection with the accompanying drawing of two illustrative embodiments of the invention herein presented for illustrative purposes.

In the drawing:

Fig. 1 is a longitudinal section, on an enlarged scale, of an electron discharge tube incorporating one illustrative embodiment of the present invention;

Fig. 2 is a cross-section of the electrode assembly shown in Fig. 1, on line 2—2 of said figure, and on a more enlarged scale;

Fig. 3 is a longitudinal section, on an enlarged scale, of an electron discharge tube constituting another illustrative embodiment of the invention;

Fig. 4 is a cross-section of the electrode assembly shown in Fig. 3, on line 4—4 of said figure, and on a more enlarged scale than the latter; and

Fig. 5 shows diagrammatically the tube illustrated in Figs. 1 and 2 and an illustrative circuit for the device.

I have discovered that if a positively charged thin wire auxiliary electrode, of which the cross-sectional diameter is below a certain critical value, described below, be inserted in an electron discharge tube adjacent the cathode, and be charged to a suitable positive potential, said thin wire auxiliary electrode will produce a sufficiently high ratio of increase in plate current to current drawn by said thin wire auxiliary electrode to reduce the current drawn by said thin wire auxiliary electrode to below an objectionable level.

For convenience the invention will be described and illustrated with one or more of my novel auxiliary electrodes added to a triode, but it is to be understood that such novel electrodes can be added with like advantage in other electron discharge tubes having two or more electrodes.

Referring more particularly to Fig. 1, the illustrative embodiment of the invention therein dis-

2

closed comprises a vacuum tube consisting of an hermetically sealed envelope 2 of glass or other suitable material and containing an electrode assembly comprising an electron-emissive cathode 4, an anode or plate 6, a control grid 8 and my novel thin wire auxiliary electrode 10 of tungsten or any other suitable metal or alloy. In the present embodiment of the invention the cathode illustratively consists of a filament of the thermionic type but the invention contemplates the use of a cathode of any suitable type, cross-section or structure. Any suitable grid may be used, circular, or of any other suitable type. In this illustrative embodiment of the invention the grid 8 is elliptical in cross-section and said cathode filament 4 extends through the center of the ellipse perpendicularly to the plane of the drawing (see Fig. 2). My novel thin wire auxiliary electrode 10 extends substantially parallel to said cathode and intersects the major axis of the ellipse at a point between said cathode and said grid 8. However, instead of being straight, my novel thin wire auxiliary electrode may be of any other suitable shape. Said cathode filament 4 and said thin wire auxiliary electrode 10 pass through the upper and lower spacer members 3 and 5 of mica or other suitable material, their upper ends being secured to resilient wires 7 and 9 respectively, said wire 7 being connected to the upper end of conductor 11 and said wire 9 to the upper end of a dummy post 13. Said conductor 11 and post 13 extend through apertures in said two spacer members 3 and 5, their lower ends being sealed through a press 15 formed upon the top of the reentrant stem 17 of said envelope 2, said envelope having its lower edge hermetically sealed to the flare 12 of said stem 17. The lower end of conductor 11 is connected to a lead-in wire 17'. The anode or plate 6 is supported by two side bars 16 and 18 having their lower ends sealed in said press 15, the bar 18 serving as a conductor for said plate 6 and having its lower end joined to a lead-in conductor 19 sealed through said press. The grid is carried by posts 20 and 21. The lower ends of said cathode filament 4 and the thin wire auxiliary electrode 10 are connected by conductors 22 and 23 to lead-in wires 24 and 25 respectively, sealed through said press 15, and the grid post 20 is connected by a wire 26 and conductor 27 to a lead-in wire 28 also sealed through said press 15.

The cathode 4 may be heated in any suitable manner as by a battery 29 (see Fig. 5), for example, and the cathode-anode circuit comprises

a source of D. C., such as a battery 30, the positive pole of which is connected to the lead-in wire 19 of said plate 6 by conductor 31 containing a resistance 32, the negative of said battery 30 being connected to the cathode 4 by a conductor 33. The grid 3 is connected to the cathode 4 by a conductor 36 through condenser 37, the signal input 38 and conductors 39, 40 and 33. An output circuit is diagrammatically indicated at 41 and is connected across the resistance 32. A conventional grid leak comprising a suitable resistance 43 will preferably be provided as shown in Fig. 5.

As above stated, I have discovered that the cross-sectional diameter of my novel thin wire auxiliary electrode 10 should be below a certain critical value which I have found to be about 0.0015 inch.

The addition of my novel thin wire auxiliary electrode 10, of which the cross-sectional diameter is below the critical value specified, furthers the flow of electrons from the cathode to the anode and produces a ratio of increase in plate current to current drawn by said thin wire auxiliary electrode that is sufficiently high to reduce the current drawn by said thin wire auxiliary electrode below an objectionable level. It will be noted that no current-limiting resistance is required in said thin wire auxiliary electrode circuit.

The smaller the cross-sectional diameter of said thin wire auxiliary electrode below the aforesaid critical value, the higher will be the ratio of plate current to current drawn by said thin wire auxiliary electrode, but there is a limit to the thinness of the wire auxiliary electrode beyond which the said thin wire auxiliary electrode becomes too frail to be usable. I have found that in practice it is not advisable to use a thin wire auxiliary electrode, the cross-sectional diameter of which is less than about 0.0005 inch, except possibly in cases where the wire possesses unusual tensile strength.

I have also discovered that the favorable ratio of increase in plate current to auxiliary electrode current attributable to the action of my novel thin wire auxiliary electrode is also dependent on its spacing from the cathode and below a certain critical spacing varies with the spacing of said thin wire auxiliary electrode from the cathode. The nearer the thin wire auxiliary electrode is to the cathode, the higher will be the ratio of increase in plate current to current drawn by said thin wire auxiliary electrode. In this connection certain factors are to be considered. For example, in use there is always more or less vibration of the thin wire auxiliary electrode and of the cathode filament, and the spacing of said thin wire auxiliary electrode relatively to the cathode must not be so close as to risk short-circuiting from this cause. If said thin wire auxiliary electrode and the filament are under suitable tension, the spacing from each other may be less than if this is not the case, but the tensile strength of a wire or filament varies and such variation may therefore have a bearing on the spacing of the thin wire auxiliary electrode from the filament. In shorter tube structures the filament, and therefore the thin wire auxiliary electrode, are shorter, and therefore the amplitude of vibration tends to be less, another factor to be considered in determining the spacing.

For the above reasons I have found that it is generally inadvisable to place the thin wire auxiliary any nearer to the cathode than about 0.007 inch. On the other hand, I have discovered that

the thin wire auxiliary electrode should be spaced from said cathode a distance below a critical value which is about 0.015 inch; otherwise the increment to the plate current becomes of the order of the wire current with respect to changes in the positive potential on the thin wire auxiliary electrode.

The illustrative embodiment of the invention shown in Figs. 3 and 4 may and preferably will be the same as the above-described illustrative embodiment of the invention shown at Figs. 1 and 2, with the exception that a second thin wire auxiliary electrode 45, in accordance with my invention, has been added. All the other parts illustrated in said Figs. 3 and 4 have therefore been designated by the same reference numerals as the corresponding parts of the illustrative embodiment of the invention shown in Figs. 1 and 2.

Referring to said Fig. 3, the second thin wire auxiliary electrode 45 of my invention is connected at its upper end by a resilient wire 42 to the upper end of the conductor 13 and at its lower end to conductor 23 to which the other thin wire auxiliary electrode 10 is connected as previously described, so that the lead-in wire 25 connects both thin wire auxiliary electrodes 10 and 45 to a conductor 44 (see Fig. 5) connected to the cathode-anode circuit containing the aforesaid battery 30. Both of said thin wire auxiliary electrodes 10 and 45 thus receive a positive potential.

The addition of this second fine wire auxiliary electrode 45 in accordance with my invention adds a material increment to the increment added to the plate current by the thin wire auxiliary electrode 10. I have found that with the two thin wire auxiliary electrodes 10 and 45, the increment added to the plate current is substantially double the increment added by the single thin wire auxiliary electrode 10. It will be apparent that additional thin wire auxiliary electrodes in accordance with my invention may be added without departing from the scope of the present invention.

It will be noted that in both the illustrative embodiments of the invention above described, the supports for the thin wire auxiliary electrodes are so situated that no undesired current from the cathode can flow to them. Where there is danger of a discharge from the cathode-emitting surface flowing to the conductive supports of the thin wire auxiliary electrodes, means may be provided to prevent it by making said supports of non-conductive material or coating them with a non-conductive material, for example.

Wherever the expression "a plurality" is used in the specification and appended claims, it is to be understood as meaning two or more.

I am aware that the present invention can be embodied in other specific forms without departing from the spirit or the essential attributes thereof, and I therefore desire the present description to be considered in all respects as illustrative and not restrictive, reference being had to the appended claims rather than to the aforesaid description to indicate the scope of the invention.

What is claimed is:

1. An electron discharge tube comprising an hermetically sealed envelope containing an electrode assembly comprising an electron-emissive cathode, an anode, and a thin wire auxiliary electrode adjacent said cathode, the cross-sectional diameter of said auxiliary electrode being less than a critical value of about 0.0015 inch, and the spacing of said auxiliary electrode from said cathode being less than a critical value of about 0.015 inch.

2. An electron discharge tube comprising an hermetically sealed envelope containing an electrode assembly comprising an electron-emissive cathode, an anode, and a thin wire auxiliary electrode extending substantially parallel to said cathode adjacent the latter, the cross-sectional diameter of said auxiliary electrode being less than a critical value of about 0.0015 inch, and the spacing of said auxiliary electrode from said cathode being less than a critical value of about 0.015 inch.

3. An electron discharge tube comprising an hermetically sealed envelope containing an electrode assembly comprising an electron-emissive cathode, an anode, a grid, and a thin wire auxiliary electrode adjacent said cathode, the diameter of said auxiliary electrode being less than a critical value of about 0.0015 inch, and the spacing of said auxiliary electrode from said cathode being less than a critical value of about 0.015 inch.

4. An electron discharge tube comprising an hermetically sealed envelope containing an electrode assembly comprising an electron-emissive cathode, an anode, and a plurality of thin wire auxiliary electrodes adjacent said cathode, each of said auxiliary electrodes having a cross-sectional diameter that is less than a critical value of about 0.0015 inch, and the spacing of said auxiliary electrode from said cathode being less than a critical value of about 0.015 inch.

5. An electron discharge tube comprising an

hermetically sealed envelope containing an electrode assembly comprising an electron-emissive cathode filament, an anode, and a thin wire auxiliary electrode adjacent and substantially parallel to said cathode, the cross-sectional diameter of said auxiliary electrode being less than a critical value of about 0.0015 inch, and the spacing of said auxiliary electrode from said cathode being less than a critical value of about 0.015 inch.

10 6. An electron discharge tube comprising an hermetically sealed envelope containing an electrode assembly comprising an electron-emissive cathode, an anode, and a thin wire auxiliary electrode adjacent said cathode, the cross-sectional diameter of said auxiliary electrode being less than a critical value of about 0.0015 of an inch.
